UNITED STATES PATENT OFFICE.

GEORGE McMANUS, OF NEW YORK, N. Y.

DESIGN FOR A STATUETTE.

40,457.

Specification for Design. Patented Jan. 25, 1910.

Application filed November 23, 1909. Serial No. 529,655. Term of patent 7 years.

To all whom it may concern:

Be it known that I, GEORGE McMANUS, residing at New York city, borough of Manhattan, in the county of New York and State of New York, have invented a new, original, and ornamental Design for Statuettes, of which the following is a specification, reference being had to the accompanying drawing, forming part thereof.

The figure is a side view partly in perspective showing the design of the statuette.

I claim:

The ornamental design for a statuette, as shown.

GEORGE McMANUS.

Witnesses:

M. E. McNINCH,

CHARLES S. JONES.
